(57) **CLAIM**

The ornamental design for a printer, as shown and described.

DESCRIPTION

FIG. 1 is a perspective view of the printer;

FIG. 2 is a front elevational view thereof;

FIG. 3 is a top plan view thereof;

FIG. 4 is a left-side elevational view thereof;

FIG. 5 is a right-side elevational view thereof;

FIG. 6 is a rear elevational view thereof;

FIG. 7 is a bottom plan view thereof;

FIG. 8 is a cross-sectional view thereof between line 8A-8A in FIG. 2 and line 8B-8B in FIG. 3; and,

FIG. 9 is a detail view of the portion indicated as "9" in FIG.

8.

The evenly spaced broken lines depict unclaimed parts of the printer and form no part of the claimed design. The dot-dash chain lines forming a rectangular shaped box around a portion of FIG. 8 depict an area shown as a detail view in FIG. 9, and form no part of the claimed design.

1 Claim, 7 Drawing Sheets
